Nelson M. Horner

UNITED STATES PATENT OFFICE.

WILLIAM C. STEWART, OF SWAMPSMOTT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

UPPER-PULLING DEVICE.

1,289,635.

Specification of Letters Patent.

Patented Dec. 31, 1918.

Application filed April 16, 1915. Serial No. 21,769.

To all whom it may concern:

Be it known that I, WILLIAM C. STEWART, a subject of the King of England, residing at Swampscott, in the county of Essex and 5 State of Massachusetts, have invented certain Improvements in Upper-Pulling Devices, of which the following description, in connection with the accompanying drawings, is a specification, like reference characters on the drawings indicating like parts in the several figures.

This invention relates to devices employed in the manufacture of boots and shoes and particularly to upper pulling devices for 15 drawing a shoe upper over a last before presenting the shoe to a machine for securing the upper to the sole or insole.

Before presenting a shoe to a pulling-over machine, it is frequently found necessary, 20 particularly if the last has a low receding toe and the upper is short or scant, to pull the upper forwardly on the last, both for positioning the upper lengthwise on the last and for obtaining a sufficient extent of upper 25 material for the grippers of the machine readily to seize and work over the sole or insole into position to be secured. The ordinary hand lasting pincers are usually employed for this purpose but they are found 30 unsatisfactory chiefly because they tend to chip or otherwise damage the edge of the last when fulcrumed thereon and, on welt work, they are likely to injure the upstanding rib of the insole.

35 An object of the present invention is to provide an upper pulling device adapted to reach over the edge of the last to seize the upper, with provision for relative movement of the device and the last in such relation 40 that the upper may be quickly and effectively pulled without injury to either the work or the last.

With this object in view and in accordance 45 with an important feature of the invention the upper pulling device is provided with last positioning means constructed and arranged to position the lateral surface of the last relatively to the upper pulling jaws and to maintain the last in a definite relation to 50 the upper pulling jaws during the upper pulling operation. In the illustrated embodiment, the last positioning means comprises a last engaging member including a claw which is arranged to hook over the

toe portion of the last, the member being 55 constructed to provide a firm abutment with provision for relative swinging movement between it and the gripper jaws for drawing the upper forwardly on the last.

The several features of the invention will 60 now be described in connection with the drawings illustrating a preferred embodiment thereof and will then be pointed out in the claims.

In the drawings:—

65 Figure 1 is a side elevation of an upper pulling device embodying the present invention in position on a shoe;

Fig. 2 is a modification showing an upper pulling device embodying the present invention adapted for use with a foot treadle.

70 Fig. 3 is a perspective view of the last positioning member of the upper pulling device.

75 The upper pulling device, as shown in Fig. 1, comprises a pair of coöperating curved jaws 2 and 3 which are pivoted together at 5 and have rearwardly extending members 6 and 8 which are adapted to be grasped by an operator for opening and closing the 80 jaws.

85 In accordance with this invention, in its illustrated embodiment, a last positioning member 12 is associated with the curved jaws 2 and 3. This member is pivoted at 15 to the end of a post 16 which projects downwardly and forwardly from the under side of the lower jaw 3 as the device is positioned in Fig. 1. The inner end of the member 12 terminates in an upwardly and forwardly projecting flange or claw 18 which is curved to adapt it to the longitudinal contour of the toe end of the last over which it hooks and is also curved laterally to receive the toe of the last and prevent the last 90 from being displaced laterally when strain is applied to the upper on either side of the median line of the last. In order to prevent the member 12 from breaking down or otherwise damaging the rib 22 of the insole 100 when the member is positioned on a welt insole, the member is provided with a depressed or recessed portion 23 which is located adjacent to the forward end of the member and is of sufficient width and proper 105 contour to bridge the rib on various sizes and styles of insoles. A spring 25 mounted on the pivot 15 and having its free ends

engaging the member 12 and the post, respectively, normally maintains the member tipped back against the post 16.

In the embodiment of the invention shown in Fig. 2 of the drawings, the upper pulling device is in the form of a bench pincer as distinguished from the hand pincer shown in Fig. 1. The lower jaw 3 is rigid with a bracket 26 which is supported by a bench 27 and the closing of the jaws is effected by a foot treadle 28, the outer end of which is connected through the rod 30 to a rearwardly projecting lug 32 on the jaw 2. A spring 33 having one end secured to a stud 35 on the jaw 2 and its other end attached to a lug 36 on the bracket maintains the jaw 2 in inoperative position or open with relation to the coöperating jaw 3. The jaw 3 may be adjustably positioned in the bracket by means of the holes 37 and a stud 38 which registers with a hole in the lower end of the member 6 of the jaw. The arm 16 projects from the jaw 3, as in Fig. 1, and carries the last positioning member 12.

In the use of the upper pulling device shown in Fig. 1, the workman holds the shoe in one hand, or the shoe may be held on a last spindle, and with the device in his other hand, the workman reaches as far as is necessary over the toe of the last and seizes the marginal edge of the upper between the jaws and then hooks the claw 18 over the toe of the last, the recessed portion 23 of the member 12 bridging the rib on a welt shoe insole and preventing it from becoming damaged. The shoe and the pincers are then moved relatively to each other about the pivot 15 as a fulcrum, first to pull the upper forwardly on the last, and then to pull it more nearly perpendicularly to the bottom of the last to provide sufficient extent of upper beyond the last bottom for the grippers of the pulling-over machine to seize. The last engaging member 12 insures a firm fulcrum for the pulling jaws in the various angular positions which they assume with relation to the sole in pulling the upper about the toe of the last and initially positions the toe of the last and holds the last with respect to the jaws against displacement during the pulling operation. Moreover, since the toe of the last is held against displacement during the manipulation of the jaws, the upper is pulled forwardly on the last symmetrically without extra effort by the operator. After the required tension has been applied to the upper, the operator clamps the tensioned upper to the last with his forefinger and presents the shoe to the pulling over machine.

When the device shown in Fig. 2 is used, the upper is inserted between the jaws and the toe of the last is located in the member 12 in the same manner as with the device shown in Fig. 1. The jaws are then

closed by the treadle 28 and the heel portion of the shoe is then forced downward using the pivot 15 as a fulcrum so as to effect a pulling of the upper forwardly on the last and then downwardly beyond the last bottom.

In presenting the appended claims I am fully aware of the prior invention of Eli Brothers covered by application Serial No. 46,662, filed on August 21, 1915, and it is not my intention to claim herein anything disclosed in said application.

Having described my invention, what I claim as new and desire to secure by Letters Patent of the United States is:—

1. An upper pulling device comprising, in combination, coöperating jaws pivoted together, means for opening and closing said jaws, and means connected to one of said jaws and constructed and arranged to present the toe of the last in a fixed relation to the jaws and to provide a fulcrum relatively to which leverage may be applied for pulling the upper about the last.

2. An upper pulling device comprising, in combination, coöperating upper and lower jaws pivoted together, means for opening and closing said jaws, and a last positioning member pivotally connected to one of said jaws and adapted to hook over the toe end of the last and move with the last to protect the end of the last from injury by the jaw.

3. An upper pulling device comprising, in combination, coöperating upper and lower jaws pivoted together, means for opening and closing said jaws, and a claw carried by one of said jaws, said claw being constructed and arranged to hook over the toe of the last and hold the last against displacement during the upper pulling movement.

4. An upper pulling device comprising, in combination, coöperating upper and lower jaws pivoted together, means for opening and closing the jaws, and a last positioning member pivoted to one of said jaws, said member being constructed and arranged to position initially the toe of the last longitudinally and laterally relatively to said jaws and to restrain lateral movement of the toe of the last during relative manipulation of the last and the jaws to draw the upper over the last.

5. An upper pulling device comprising, in combination, coöperating jaws pivoted together, means for opening and closing the jaws, and a last positioning member pivotally connected to one of said jaws and adapted to engage the bottom and the side faces of the last.

6. An upper pulling device comprising, in combination, jaws to seize and pull an upper, means for opening and closing said jaws, and last engaging means operatively associated with one of said jaws and adapt-

ed to engage the bottom and side faces of the toe of the last whereby the toe of the last is controlled against displacement relatively to said jaws during stretching of the 5 upper forwardly and downwardly over the toe end of the last.

7. An upper pulling device comprising, in combination, coöperating upper and lower jaws pivoted together, means for opening 10 and closing said jaws, and a last positioning member pivotally connected to one of said jaws and adapted to hook over the toe end of the last and move with the last to protect the end of the last from injury by the 15 lower jaw when the last and the jaws are moved relatively, said member having an arched portion adapted to bridge the upstanding rib on a welt shoe insole and protect it from injury.
8. An upper pulling device comprising, in combination, coöperating upper and lower jaws pivoted together, means for opening 20 and closing said jaws, a post projecting from the lower jaw, a last positioning member pivoted on said post, said member being constructed and arranged to position the 25

toe of a last relatively to the jaws and to hold the last against lateral displacement, and a spring for maintaining said member normally in operative position. 30

9. An upper pulling apparatus comprising a base adapted for attachment to a bench and having an upright portion, a stationary jaw carried on the upright, a last positioning member pivotally mounted adjacent to the 35 stationary jaw and constructed and arranged to hold the toe end of a last in a definite relation to the said jaw during relative movement of the last and the jaw, means to maintain the pivoted member in a normal last 40 receiving position, a jaw pivoted to the upright, means to hold the pivoted jaw normally open with respect to the stationary jaw, and treadle connections for closing the pivoted jaw to hold the upper while the last 45 is moved about the axis of the pivoted support as a fulcrum to pull the upper about the last.

In testimony whereof I have signed my name to this specification.

WILLIAM C. STEWART.
